MEDAL OR SIMILAR ARTICLE

Thomas H. Jones, Washington, D. C., assignor to
the United States of America as represented
by the Secretary of the Army

Application September 29, 1952, Serial No. 21,641

Term of patent 14 years

(Cl. D29—19)

To all whom it may concern:

The invention described herein, if patented, may be manufactured and used by or for the Government for governmental purposes, without the payment to me of any royalty thereon.

Be it known that I, Thomas H. Jones, a citizen of the United States and resident of the city of Washington, in the District of Columbia, have invented a new, original, and ornamental Design for a Medal or Similar Article, of which the following is a specification, reference being had to the accompanying drawings, forming a part thereof.

Fig. 1 is a front view of a medal, showing my new design.

Fig. 2 is a side view of the same.

It is understood that my design may be em-

bodied in such articles as a medallion, badge, plaque, or sign, without departing from the spirit of my invention.

The essential features of my design are shown in full lines.

I claim:

The ornamental design for a medal or similar article, as shown and described.

THOMAS H. JONES.
